DUAL-CHAMBER ARTIFICIAL HEART

Victor W. Bolie, Ames, Iowa, assignor to Iowa State University Research Foundation, Inc., Ames, Iowa, a corporation of Iowa

Filed Feb. 27, 1963, Ser. No. 261,426

8 Claims. (Cl. 3—1)

This invention relates to a dual-chamber artificial heart, and, more particularly, to apparatus adapted to oscillate pneumatically.

It is an object of this invention to provide an artificial heart adapted for use within the chest cavity.

Another object is to provide an artificial heart operated by an automatically cycling device delivering adjustably-controlled air pulses.

Still another object is to provide a pneumatic oscillator uniquely constructed and adapted to alternately pressurize chambers such as those employed in pumping blood.

Other objects and advantages of the invention may be seen in the details of construction and operation set down in this specification.

The invention is explained in conjunction with the accompanying drawing, in which:

FIG. 1 is an elevational view, partially in section, of the artificial heart of the invention, the sectional portion corresponding to that seen along the sight line 1—1 applied to FIG. 2;

FIG. 2 is a top plan view of the organ seen in FIG. 1;

FIG. 3 is a sectional view of the organ of FIG. 2 and at a position thereof corresponding to the line 3—3 of FIG. 1;

FIG. 4 is a schematic representation, i.e., diagram, of a pneumatic oscillator employed in conjunction with the organ of FIGS. 1—3; and

FIG. 5 is a schematic representation of an alternative form of pneumatic oscillator.

In the illustration given, the numeral 10 designates generally a receptacle adapted to be installed within the chest cavity and which is constructed of a rigid material such as a rigid plastic capable of generating the least possible hemolysis, clotting, irritation, and heat.

The receptacle 10 is characterized by a pair of elongated chambers 11 and 12 (see also FIGS. 2 and 3) which extend downwardly from an open top 13. The shape of the receptacle 10 is generally oval or ellipsoidal. Centrally, the top 13 of the receptacle 10 is equipped with a pair of upwardly-extending integral tubes 14 and 15, which communicate as at 16 and 17 with the chambers 11 and 12, respectively. The interior walls of the chambers 11 and 12 are grooved annularly as at 18 and 19 to permit pressure fluid entering the tubes 14 and 15 to surround the collapsible bags 20 and 21. The bags 20 and 21 provide the pumping means for the artificial heart.

As seen in FIG. 3, the interior walls of chambers 11 and 12 are further equipped with vertically extending recesses as at 22 and 23, which merge as at 24 and 25 at the bottom of the chambers so as to insure full access of pressure fluid to all of the exterior portions of the bags 20 and 21.

Each bag 20 and 21 is equipped with an upstanding constricted outlet portion as at 26 and 27, respectively. Each portion 26 and 27 is equipped with an inlet check valve and an outlet check valve, the outlet check valve of the bag 20 being illustrated in FIG. 1 and designated by the numeral 28, while the inlet check valve associated with the bag 21 is seen at the left-hand side of FIG. 1 and is designated 29. The inlet check valve associated with the bag 20 is seen in FIG. 2 and is designated 30,

2

while the outlet check valve associated with the bag 21 is seen also in FIG. 2 and is designated by the numeral 31.

Functionally, looking at the showing in FIG. 1 as representing the artificial heart of a mammal, with the bag 21 corresponding to the right ventricle and the bag 20 to the left ventricle, the outlet check valve 31 allows flow to the lungs and thus corresponds to the pulmonary valve. The inlet check valve 29 allows flow from the vena cava, and corresponds to the tricuspid valve. Relative to the left ventricle replaced by the bag 20, the outlet check valve 28 corresponds to the aortic valve leading to the mammal's aorta, while the inlet check valve 30 carries the blood flow from the lungs and corresponds to the mitral valve.

It will be appreciated that the bags 20 and 21 are constructed of semi-pliable, i.e., flexible or resilient, material adapted to change shape upon change of external pressure—in the portions below the constricted upper portions 26 and 27. As seen in FIG. 1, the upper neck-like portions 26 and 27 are constructed of relatively thicker plastic material so as to resist deformation and are adapted to receive the tubes extending into the vena cava, pulmonary artery, pulmonary veins and aorta. Preferably, the constricted portions 26 and 27 merge into the thinner walls of the major portions of the bags 20 and 21 by virtue of tapering wall thicknesses as at 32 and 33.

FIGS. 4 and 5 show variations of pneumatic power operators constructed specially so that they sequentially and automatically alternate pressure and suction to each ventricular chamber 11 and 12 from steady sources of constant air pressure P and suction S. Also provided are means for adjusting the cycle time and air pulses to the left and right chambers.

If desired, the pneumatic oscillator may be located externally of the body, giving externally controllable heart rate and left and right heart output stroke volumes. Alternatively, internal installation of the pneumatic oscillator is achievable, utilizing an internal biological gas generator (possibly stomach hydrochloric acid and plasma sodium bicarbonate to evolve CO₂, which is non-toxic and re-absorbable).

The oscillator seen in FIG. 4 employs two four-way valves 34 and 35, each of the single pilot-operated, spring-return type. Each of the valves 34 and 35 is equipped with a spool as at 36 and 37 which is spring-loaded as at 38 and 39 so as to be biased in one direction. The four-way designation of each valve stems from the fact that four flow passages or ways are provided by positioning the spool as at 40 and 41 shown in heavy line relative to the valve 34 and as at 42 and 43 shown in dotted line. The corresponding ways in the valve 35 are designated 44, 45, 46 and 47, respectively.

The valve 34 is connected to a source P of compressible pressure fluid (such as air) by means of conduits 48, while the valve 35 is coupled to the receptacle 10, namely, the tubes 14 and 15, by means of conduits or pipes 49. The valves 34 and 35 may be Modernairs, or the four-way, single pilot-operated, two-position type provided by Schrader Air Valve Company, of New York city.

In the position shown, the way 41 communicates the pressure source P with a first tank or reservoir 50 by means of the conduit line 51, the line 51 being equipped with a check valve 51a. Also, the line 51 communicates with a flow control device 52 which has adjustable flow in one direction via the adjustable constriction 53 and full flow in the other direction by virtue of the check valve 53a. Such a control valve is available as Modernair, No. 100, or from the Schrader Air Valve Company. The flow control valve 53a connects with one side of a two-way double pilot-operated valve 54, the two ways being designated 55 and 56. The way 55 is seen to com-

municate the atmosphere A with the pilot ports 57 and 58 of the four-way valves 34 and 35 by means of pipe 59.

Thus, in the solid line configuration of the ways within the valves 34 and 54, compressed air is being delivered to the tank 50 and gradually building up in the pilot port 60 of the two-way valve 54 so as to shift the spool 61 thereof downwardly, thereby establishing the other way 56. Meanwhile, however, the way 55 vents the pilot ports 57 and 58, permitting the springs 38 and 39 to maintain the spools 36 and 37 in the bottom position.

Simultaneously with this condition, the reservoir 62 is connected with one of the pipes 49 via the way 45. It will also be noted that the conduit 63 establishing this connection also is in communication with the port 64 of the two-way valve 54 by means of the open check valve 65. Thus, as pressure is built up in the port 60 by virtue of pressure fluid flowing through the constriction 53, ultimately the spool 61 moves to the downward condition.

When this happens, i.e., the spool 61 being shifted to the downward condition, the way 56 is established, which communicates with the pressure source P, whereupon pressure fluid is delivered through the line 59 to the ports 57 and 58 to move the spools 36 and 37 upwardly against the bias of the springs 38 and 39. This then establishes the dotted line ways 42, 43, 46 and 47. With this condition established, pressure fluid from the source P flows through the way 42 and conduit 66 (through the open check valve 67) to the reservoir 62. Simultaneously, pressure fluid moves through the constricted portion 67 of the flow control valve 68 to build up pressure at the port 64 and ultimately move the spool 61 to the upper condition. This is made possible by virtue of the fact that the port 60 communicates with the tank 50 and the way 46 by means of the open check valve 53a. By virtue of the fact that pressure fluid flows out of the reservoir 50 and through the way 46, a lower pressure exists at the port 60 than that which can be established at the port 64 by virtue of the build-up through fluid flow through the constriction 67. Pressure fluid passing through the way 46 enters the upper of the two pipes 49, while the lower pipe is connected to suction. Thus, the tubes 14 and 15 are alternately and sequentially subjected to pressure and suction to cause corresponding distortions of the bags 20 and 21, thereby effecting the desired heart pumping action.

A modified form of pneumatic oscillator is seen in FIG. 5, wherein only two four-way valves are employed, there being no need in this case for the two-way valve 54 seen in FIG. 4. Further, each of the four-way valves 70 and 71 are double pilot-operated, and may be Modernair CRV405, or those provided by the Schrader Air Valve Company. Employed in combination with these valves are two variable volume reservoirs 72 and 73, which may be Schrader No. 30901-0030 cylinders having a 1" bore and 3" stroke.

Also employed in the pneumatic power oscillator system of FIG. 5 are two flow control valves 74 and 75 of the Modernair type No. 100 used in the illustration of FIG. 4. Still further, check valves as at 76 and 77 are employed which may be Schrader No. 3134.

The condition of the apparatus seen in FIG. 5 is to deliver compressible pressure fluid to the left ventricle chamber 14. Starting with the reservoir 72, it is seen that pressure fluid from this storage tank is enabled to flow through the line 78, then through the way 79 and pipe 80 to the way 81 which communicates with the tube 14 as soon as the spool 95 of valve 71 shifts to the left. Simultaneously, pressure fluid from the source P flows through the way 82 in the valve 70 and thence through the line 83 to a T 84. One branch of the T 84 communicates with the alternate reservoir 73 by means of a line 85, while the other branch of the T 84 communicates with the flow control valve 74 by means of a line 86. The flow control valve 74 is arranged so that pressure fluid in the line 86 can only flow through the metered

side, i.e., the constriction 87, into the pilot port 88 associated with the right-hand side of the four-way valve 70. In this situation, the check valve portion 89 of the flow control valve 74 is closed. This results in a gradual build-up at the pilot port 88 to shift the spool 89 of the valve 70 to the left position, i.e., where the ways are shown in dotted line. This shifting is able to take place because the left-hand pilot port 90 is connected to a low pressure line at this time. Any pressure fluid in the pilot port 90 is able to flow through the check valve portion 91 of the flow control valve 75 into the line 78 delivering pressure fluid to the left ventricle chamber 14.

As soon as sufficient pressure is developed in the pilot port 88 to shift the spool 89 to the left position, pressure fluid from the source P flows through the dotted line way 92 into the reservoir 72 and simultaneously by means of the line 93 through the constriction 94 into the pilot port 90. This in time develops sufficient pressure at the pilot port 90 to shift the spool 89 to the right position. Thus, there is provided an automatic oscillation in the valve 70 which alternately communicates the reservoirs 72 and 73 (seen to be of the adjustable volume type by means of the pistons 72a and 73a, respectively) to the outlet valve 71.

In the condition shown in FIG. 5, pressure fluid is being delivered through the way 81a to the right ventricle chamber 15, while the left ventricle chamber 14 is connected to a source of suction S. In the left position of the spool 95 provided as part of the valve 71, the dotted line ways are established wherein the right ventricle chamber 15 is coupled to suction and the left ventricle chamber 14 is connected to a source of pressure P. The shifting of the spool 95 is achieved very shortly after the shifting of the spool 89, and for this purpose the valve 71 is equipped with right and left pilot ports 96 and 97, respectively. In the condition shown, pressure is being built up in the pilot port 96 to ultimately shift the spool 95 to the left position. This stems from the fact that the compressible pressure fluid escaping from the storage tank 72 through way 79 of valve 71 cannot pass out way 81 of valve 71 until spool 95 has shifted to the left. In order to overcome any possible sluggishness of action of valve 70 due to friction of its sliding spool, positive feedback to its pilot ports 88 and 90 is provided through the one-way check valves 76 and 77. In this way, the spools of valves 70 and 71 alternate left and right automatically at a rate controllable by the flow constrictions 87 and 94, and thus alternate pressure and suction pressures to the left and right ventricles connected to lines 14 and 15. If the ventricular back pressure does not exceed its maximum physiological value (3 to 5 p.s.i.g.), and the supply pressure P is high (90 to 100 p.s.i.g.), then the ventricular stroke volumes delivered by the device are governed by the adjustable volumes 72 and 73.

While, in the foregoing specification, a detailed description of the invention has been set down for the purpose of illustration, many variations in the details herein given may be made by those skilled in the art without departing from the spirit and scope of the invention.

I claim:

1. In an artificial heart, a rigid receptacle adapted to be installed in a body cavity and defining a pair of chambers, said receptacle comprising a generally elliptical body with said chambers being disposed in side-by-side, longitudinally-extending relation, a flexible bag in each chamber equipped with inlet and outlet check valves, each bag comprising a generally elongated hollow body having a constricted end, the wall of said body at said constricted end being relatively thicker than the wall of the remainder of said body, said valves being mounted in side-by-side relation in said constricted end, pressure fluid conduit means communicating with each chamber adapted to alternately compress said bags, said conduit means being coupled to each chamber

adjacent one end thereof, with flow passages for said pressure fluid in the chamber walls communicating with the other chamber ends, and a pneumatic oscillator coupled to said conduit means, said oscillator comprising a pair of pilot-operated, four-way valves, one of said valves being coupled to said pipe means, a source of pressure fluid coupled to other of said valves, a pair of pressure fluid reservoirs coupled to both of said valves, and other conduit means including constriction means coupling said reservoirs to said valve for operating said valves.

2. In an artificial heart, a substantially rigid receptacle adapted to be installed in a body cavity and defining a pair of chambers, a flexible bag in each chamber equipped with inlet and outlet check valves, flexible pressure fluid conduit means communicating with each chamber, and a pneumatic oscillator coupled to said conduit means for delivering pressure fluid to said chambers for alternately compressing said bags, said oscillator including a pair of pilot-operated, four-way valves, one of said valves being coupled to said conduit means, a source of pressure fluid coupled to the other of said valves, a pair of pressure fluid reservoirs coupled to both of said valves, and other conduit means including constriction means coupling said reservoirs to said valves for simultaneously operating said valves.

3. The structure of claim 2 in which the said one valve is also coupled to suction means for expanding said bags.

4. The structure of claim 2 in which said conduit means includes a three-way valve equipped with a shiftable spool, and pilot ports communicating with the spool ends, said source and one reservoir being coupled to said ports in one condition of the other of said four-way valves, which said source and the other reservoir are reversely coupled to

5
said ports in the other condition of said other four-way valve.

10 5. The structure of claim 2 in which each of said reservoirs is equipped with means for varying the internal volume thereof.

6. In combination, a pair of pressurizable chambers adapted to function as an artificial heart, a pneumatic oscillator including first and second four-way valves each equipped with a movable spool, a source of pressure fluid coupled to said first valve, pipe means coupling said chambers to said second valve, a pair of pressure fluid reservoirs, and conduit means interconnecting said valves and reservoirs for delivering pressure fluid for simultaneously moving said spools to alternately communicate each of said reservoirs with different valves.

15 7. The structure of claim 6 in which said conduit means is equipped with variable constriction means for regulating the period of oscillation of said oscillator.

20 8. The structure of claim 6 in which means are provided for controllably varying the volumes of said reservoirs whereby the ventricular stroke volumes generated by said oscillator are adjustable.
